UNITED STATES PATENT OFFICE.

EDWARD F. SMITH, OF PORTLAND, OREGON.

NAP-BRUSHING MACHINE.

1,285,438.

Specification of Letters Patent. Patented Nov. 19, 1918.

Application filed December 5, 1914. Serial No. 875,568.

To all whom it may concern:

Be it known that I, EDWARD F. SMITH, a citizen of the United States, residing in the city of Portland, county of Multnomah, and 5 State of Oregon, have invented certain new and useful Improvements in Nap-Brushing Machines, of which the following is a specification.

My invention relates to nap brushing machines, and more particularly to a machine especially adapted for brushing and straightening up the nap of blankets and the like after they have been washed, it being, therefore, particularly well adapted for laundry 15 use.

Among the salient objects of my invention are,—to provide a machine of the character referred to into which a blanket or the like can be started and automatically fed 20 through the machine and thoroughly brushed in a manner which will straighten the nap and give a new and fluffy appearance to the blanket as it passes through the machine; to provide in a machine of the character referred to means for drawing off the loose 25 nap and lint during the operation of the machine, and therefore preventing its escape into the atmosphere of the room; to provide a simple and efficient mechanism for feeding 30 the blanket through the machine, with the brush-operating mechanism geared to a speed in relation thereto which insures that every part of the blanket will be repeatedly 35 brushed and the nap properly straightened out before it passes beyond the brushes; to provide in a machine of the character referred to an adjustable brushing table whereby it is easy to hold the blanket in 40 proper relationship to the brushes to get the best results; and, in general, to provide a simple and efficient machine which will quickly and economically brush a blanket after it has been washed without damage thereto.

45 In order that others may thoroughly understand my invention, I have shown one practical embodiment thereof on the accompanying sheet of drawings, which I will now describe.

50 Figure 1 is a front elevation of a machine embodying my invention, with parts broken away to reduce the size of the figure;

Fig. 2 is a vertical sectional view, taken transversely of the machine, on line 2—2 of 55 Fig. 1; and

Fig. 3 is an end view of the machine shown in Fig. 1.

Referring now to the drawings more in detail, I have provided supporting legs, as 1—1, which may be suitably spaced and secured together in any desirable manner. Pivotedly mounted in the upper part thereof, on a shaft 2, is a table frame 3, having a concaved table top or brushing top, as 4, extending throughout the length of the machine. As a means for raising and lowering said table frame, I have provided cam members, as 5—5, secured to a shaft 6, rotatably mounted in the legs 1, with an operating hand lever 7, working in a guide frame 8, whereby said table can be rocked on its shaft bearing 2 for a purpose hereinafter again referred to. Rotatably mounted upon the front top part of said supporting legs, in suitable bearing boxes 9—9, is a feed 75 roller 10, provided with numerous small feed pins, as 11, projecting therefrom for holding and feeding the blanket, which is designated B, through the machine.

Rotatably mounted upon said machine, in 80 suitable bearing boxes, as 12—12, at the opposite ends thereof, is a revoluble brush member 13, comprising a shaft 13^a, and a body 13^b, with four rows of brush bristles 13^c, extending throughout the length of the 85 machine, substantially in the manner shown, said brush bristles being arranged to strike the blanket B upon the concaved table top 4, as clearly indicated in Fig. 2. The shaft 13^a of said brush is provided at one end with 90 fast and loose pulleys, as 14 and 15, respectively, and at its opposite end said shaft is provided with a worm 16, and a hand wheel 17, as indicated. Said worm 16 meshes with 95 and drives a worm-gear 18, mounted upon a short shaft 19, in a bearing box 20, and upon which shaft 19 is a beveled gear 21, adapted to mesh with a beveled gear 22, slidably keyed to a shaft 10^a of the feed roller 10, whereby said feed roller 10 can be thrown 100 out of driving connection with the other mechanism at will by any suitable operating means connected to the clutch ring, as at 22^a, of the gear 22. Thus it will be noted that the brush member 13 is driven very much 105 faster than is the feed roller or member 10, thereby insuring a great many strokes of the brush on each part of the blanket as it advances slowly through the machine, and thoroughly brushing and straightening out 110

the nap thereof. Mounted rearwardly and above the brushing mechanism is a hood 23, which extends downwardly into close proximity to the finish of each stroke of the 5 brushes on the blanket, and is provided with a hinged lip, as 24, extending the full length thereof, and is adapted to regulate the size of the opening between the lower edge of the hood and the table top 4, so as 10 to get the best suction action near the brushes. Said hood is connected at its top with a suction fan (not shown) through the pipe 25, whereby the loose nap and lint is carried off and may be discharged into a 15 bag or other receptacle at any desired location. I prefer to divide the interior of said hood, as by partitions 23^a—23^b, arranged to insure uniform suction throughout the length of the lower edge of the hood.

20 I am aware that many changes can be made in the embodiment of the invention here shown for purposes of illustration, and I do not limit the invention to this particular form, except as I may be limited by the 25 hereto appended claims.

I claim,—

1. A nap brushing machine of the character referred to comprising in combination a supporting structure, a brushing table 30 having a fixed concaved upper surface extending lengthwise thereof, a revoluble feeding member extending lengthwise of said structure adjacent said brushing table, a revoluble brushing device supported 35 lengthwise of said structure above said brushing table, means for driving said brushing device and said feeding member at different speeds, said brushing device being driven in the direction of the feed 40 movement of the article being brushed, and adapted to engage the article against the concaved surface of said brushing table, and a suction hood extending lengthwise of said brushing table in close proximity to the 45 article being brushed and to the revolving brushing device, substantially as and for the purpose described.

2. A nap brushing machine of the character referred to comprising in combination 50 a supporting structure, a brushing table having a fixed concaved upper surface extending lengthwise thereof, a revoluble feeding member extending lengthwise of said structure adjacent said brushing table, a revoluble 55 brushing device supported lengthwise of said structure above said brushing table, means for changing the space between the revolving brushing device and the concaved upper surface of the brushing table, means 60 for driving said brushing device and said feeding member at different speeds, said brushing device being driven in the direction of the feed movement of the article

being brushed, and adapted to engage the article against the concaved surface of said 65 brushing table, and a suction hood extending lengthwise of said brushing table in close proximity to the article being brushed and to the revolving brushing device, substantially as and for the purpose described. 70

3. A nap brushing machine of the character referred to, comprising a supporting structure, an adjustable brushing table, having a fixed concaved upper surface, extending lengthwise thereof, a revoluble feeding member extending lengthwise of said structure adjacent said brushing table and adapted to feed a blanket, or the like, over said table, a revoluble brushing device supported lengthwise of said structure above 80 said table, and provided with a plurality of spaced rows of brush bristles extending lengthwise thereof, means for driving said brushing device and said feeding member at different speeds, said brushing device being 85 driven in the direction of the feed movement of the article being brushed, and adapted to engage the article against the concaved surface of said brushing table, a suction hood extending lengthwise of said 90 brushing table and above the same, and means for regulating the suction action thereof in connection with said brushing device, substantially as described.

4. A nap brushing machine of the character shown and described comprising in combination, a supporting structure, a brushing table mounted thereon and extending lengthwise thereof, a revoluble feeding device mounted upon said structure, adjacent said brushing table, in a position slightly above and in front of the same, whereby a blanket or other article to be brushed is fed in a downwardly inclined direction from said feeding device on to said brushing table, a revoluble brushing device supported lengthwise of said structure above said table, means for driving said brushing device and said feeding member at different speeds, said brushing device being driven in 100 the direction of the feed movement of the article being brushed and at a high speed, and adapted to engage the article against the surface of said brushing table as said article moves downwardly in an inclined 105 position on to said brushing table, and a suction hood overhanging said brushing table and said brushing device, in close proximity thereto, substantially as and for the purpose described. 110

Signed at Portland, Oregon, this 25th day of November, 1914.

EDWARD F. SMITH.
